EXPANSIBLE COP HOLDER

Horace H. Raymond, Berlin, Conn., and Royal Little, Providence, R. I., assignors to Atlantic Rayon Corporation, Providence, R. I., a corporation of Rhode Island

Application October 29, 1940, Serial No. 363,272

10 Claims. (Cl. 242—72)

This invention relates to expandable mandrels or cop-holders for supporting packages of yarn, thread and the like in winding the same on a central core.

The present improved mandrel or package-holder is especially adapted for use with twisting frames, winding machines and like textile apparatus in which the yarn or other material is wound on a fiber or paper tube forming the core of the package.

One object of the present invention is to provide an expandible mandrel of the type indicated adapted to grip the paper cop-tube securely thereon for rotation with the mandrel.

Another object of the invention is to provide a cop-holder of the type indicated having convenient means for expanding and contracting the periphery of the mandrel so that the tube may be readily placed thereon and the tube and wound package removed therefrom.

Another object of the invention is to provide an expandible cop-tube holder or mandrel having its periphery expandible by means of a key-like lever which is locked to the mandrel when the latter is contracted and free to be removed therefrom when the mandrel is expanded.

Another object of the invention is to provide a mandrel or cop-holder having means providing for a concentric disposition of its periphery when expanded.

Further objects of the improvement are to provide a device of the type indicated which is simple in construction, economical to manufacture, and efficient in use for the purposes intended.

A preferred embodiment of the invention, together with a modified form of construction of the cop-holder or mandrel, are described in the following specification, by way of example, and illustrated by the accompanying drawings. In the drawings:

Fig. 1 is a side view of the present improved cop-holder or mandrel represented as supporting a package of yarn or the like with the cop-tube and yarn mass shown in section;

Fig. 2 is a longitudinal sectional view of the same taken through the axis of the holder;

Fig. 3 is an end view of the holder or mandrel;

Fig. 4 is a sectional view of the holder on line 4—4 of Fig. 2;

Fig. 5 is a view of the end of the holder opposite from that shown in Fig. 3;

Fig. 6 is a longitudinal sectional view of the holder showing the key-expander locked in place with the periphery of the holder contracted to adapt it to receive the cop-tube;

Fig. 7 is an end view of the holder corresponding to the showing in Fig. 6;

Fig. 8 is a transverse sectional view of the holder on line 8—8 of Fig. 6;

Fig. 9 is a transverse sectional view of the holder on line 9—9 of Fig. 6;

Fig. 10 is a perspective view of the key-lever for expanding the holder;

Fig. 11 is a longitudinal sectional view of a holder of modified form of construction; and

Figs. 12 and 13 are detailed views of the same.

As herein illustrated the invention is in the form of a mandrel or holder for paper or fiber cop-tubes of a diameter relatively large in proportion to their length. Such tubes are employed for winding cops or packages of cotton, silk and rayon yarn in twisting it from supply bobbins or the like with the packages driven by surface contact with a drive-roll or drum. For this purpose the mandrel or cop-tube is provided with gudgeons at its ends adapted to seat in the sockets of a fork-like arm or bracket, not shown, the arm being either stationary or in some instances pivoted to swing to permit the mandrel to move away from the drive-roll as the yarn is built up on the cop-tube supported by the mandrel.

In a preferred form of construction, shown in Figs. 1 to 10, inclusive, the mandrel 2 comprises spaced end-heads 3 and 4 having hubs 5 secured fast on an axial spindle 6. The end-heads 3 and 4 may be constructed as castings or formed from sheet-metal and the hub 5 of each head has a drive fit on a knurled or scored portion 8 of the axial shaft or spindle 6 to connect the heads rotatably therewith. The spindle 6 is formed with annular grooves 7 adjacent their knurled portions 8 with split rings 10 sprung into the grooves and abutting the ends of the hubs 5 of the heads 3 and 4 to locate the heads on the spindle. The head 3 is recessed or cupped to form an annular flange 11 terminating at the outside in a radial flange or rim 14. The opposite head 4 is provided with a somewhat thicker annular flange 15 which is extended in a beveled or inclined rim 16 whereof to form a V-shaped groove 17 which is adapted for a purpose as later explained.

Surrounding the annular flanges 11 and 15 on the heads 3 and 4 is an expandible sleeve or shell 20 constructed of relatively thin sheet-metal and forming the peripheral expansion element of the mandrel. The periphery of the tubular shell 20 is interrupted by a longitudinally-extending slit or opening formed by the

terminal portions of the sheet-metal which are bent or looped around to provide two parallel inwardly-extending straight extensions 21. The greater portion of the sleeve or shell 20 is thus rendered free to expand radially by separating its terminal portions 21, that is the sides of its slit portion; it being noted by reference to Fig. 2 that the straight portions 21 are somewhat shorter than the full length of the shell to adapt them to clear the sides of the heads 3 and 4. At a point opposite from the terminal portions 21 the sleeve or shell 20 is secured fast to the rims of the end-heads 3 and 4. In order that the shell 20 when expanded shall be concentric with the axis of the mandrel, that portion 15 which is made fast to the flanges 11 and 15 is spaced therefrom by means of an arcuate spacer or filler-strip 23 underlying the shell and extending across between the two heads, see Figs. 2 and 4. As before indicated, the sleeve 20 rests upon and is supported by this filler-strip 18, being secured to the flanges 11 and 15 by means of rivets 24 and 25 extending through the filler-strip. It will be understood, therefore, that when the shell 20 is contracted as shown in Figs. 7 to 9, inclusive, due to its inherent resiliency, the sides of its split portion will be drawn inwardly toward the periphery of the flanges 11 and 15; while, on the other hand, when the shell is expanded, as indicated in Figs. 4 and 5, its inner circumference will be spaced away from the flanges in the form of a true circle or, in other words, concentric with the axis of the mandrel.

The means for expanding the sleeve or shell 20 comprises a rotatable element 26 preferably in the form of a flat strip or bar having rounded or arcuate edges adapted to engage against the flat terminal portions 21 of the shell. The ends of the expansion member 26 are mounted to rotate in circular holes 27 in the heads 3 and 4, being held from longitudinal displacement by means of ears or lugs 28 projecting from its sides. As shown in Fig. 6, the lugs 28 may be formed by striking them up from the metal of the member or by providing them in any other suitable manner. Washers 29 are located between the lugs 28 and the sides of the end-heads 3 and 4 to provide for free rotative movement of the member 26. The member 26 is thus adapted to be rotated to cause its rounded edges to slide on the inwardly-projecting portions 21 of the sleeve or shell 20 to cam them apart in the manner indicated in Figs. 4 and 5. To retain the expansion member 26 in this operative relationship a detent spring 30 is provided on the inside of the flange 15 of the head 4 with its end extending thereacross in a straight portion 31 adapted to bear against the flat side of the member 26 to restrain it against unwarranted turning after it has been operated to expand the sleeve 20. The spring 30 is curved to conform to the inner face of the flange 15 and is secured thereto by means of the rivets 25 which fasten the end of the sleeve and the filler-strip 23 to the flange, see Figs. 2 and 5.

The expansion member 26 is adapted to be operated by means of a key-lever 35, shown in perspective view in Fig. 10, having its end shaped to engage the end of the member 26 which projects through the side of the head 3. Attached 70 to the outer face of the head 3 is a loop-shaped or box-like housing 36 fastened thereto by means of rivets 37, see Figs. 2 and 3, and provided in its outer portion with a rectangular opening 38 through which the key 35 is inserted. The key 75

35 is of novel construction comprising a tubular shank 39 of rectangular shape in cross-section with a finger-piece 40 let into a slot in its outer end and secured thereto by welding or riveting. The open end of the shank 39 of the key 35 is of a size to adapt it to freely fit onto the projecting end of the expansion member 26 by inserting it through the rectangular opening 38 in the housing 36, it being noted by reference to Fig. 2 that this end of the element 26 is rounded on its edges and projects outwardly slightly beyond the opening to render it convenient to apply the key thereto. It will be noted also that the end of the shank 39 of the key 35 is somewhat beveled on its edges so as to assist in entering it through the slot 38 in the housing 36. Cut into the sides of the shank 39 of the key 35 are two opposite slots 41 which permit the key to be turned to partially rotate the element 26 in effecting expansion or contraction of the sleeve or shell 20.

Referring particularly to Figs. 6 and 7, it will be observed that when the key 35 is turned into position to permit contraction of the sleeve or shell 20 the sides of the slot 38 in the housing member 36 engage into the slots 41 in the sides of the key, thereby locking the key to the holder to prevent its removal therefrom until the expansion element 26 is turned to the opposite position to cause expansion of the shell. In other words, the key 35 remains locked to the mandrel or cop-holder at all times when the latter is contracted and can be removed only after the sleeve 20 has been expanded. By this arrangement the key serves as a precautionary measure against seating the mandrel or cop-holder in its bearings before it has been expanded to grip the cop-tube in place thereon. Likewise, there is less liability of the key being lost or misplaced when the cop-holder is removed from its bearings since it remains locked to the mandrel in convenient position to be operated again when a fresh tube is placed thereon. As a further advantage, the key 35 serves as a convenient handle for holding the mandrel when placing the cop-tube thereon or removing the tube and wound package therefrom.

Preferably, the expansion member 26 is controlled in its rotation so that it can be turned through an angle of ninety degrees only, that is from the position shown in Figs. 3 to 5 to that shown in Figs. 7 to 9. One limiting means for this control of the member 26 is in the form of an eccentric or cam-shaped washer or disk 42. The washer or disk 42 is fitted to the projecting end of the element 26 and confined within the looped housing-member 36. The periphery of the disk 42 is of generally circular shape except that it has two somewhat flattened faces 43 and 44 at its rim. These faces are shaped on a flatter arc than the main rim of the disk, that is on a radius struck from the axis of the mandrel so that they may engage and slide across the inner concentric face of the flange 11 on the head 3. The main portion of the circular rim of the disk 42 between the flattened faces 43 and 44 is of a diameter sufficiently large to prevent the rotation of the disk beyond either of the flattened faces. By the provision of this eccentric disk 42 the rotative motion of the expansion member 26 is limited to an angle of ninety degrees, that is it may be turned from the position shown in Fig. 3 to that shown in Fig. 7 in one direction only and back again in the opposite direction while being restrained from a complete rotation. This arrangement provides for

more convenient manual operation of the expansion means of the mandrel.

Fig. 11 shows a slightly modified form of construction of the mandrel or cop-holder as having the end-disks 53 and 54 struck up from sheet-metal and supported from an axial hub 55. The ends of the hub 55 are reduced in diameter to project through axial holes in the disks 53 and 54 and swaged or riveted over to secure the disks in place. The gudgeons for supporting the mandrel rotatively may be constructed as pins or pintles 58 and 59 formed with reduced shanks 60 driven into bores in the ends of the hub 55 and provided with knurled portions 61 for keying them therewith. The outer end of one of the gudgeons 58 is bored axially to receive a ball 62 pressed outwardly by means of a helical spring 63 pocketed in a smaller bore 64, the ball being held in place by swaging over the outer rim of the larger bore. This construction provides a resilient thrust-bearing for centering the mandrel in its bearing sockets. In other instances the mandrel or cop-holder may be mounted rotatably on its axial shaft for use in winding machines requiring such a form of construction.

Fig. 11 further illustrates a modified form of construction of the means for locking the expansion member 26 from turning after the sleeve or shell 20 has been expanded and also the means for limiting the turning movement of said expansion member. These two functions are performed by a single element 65 of substantially rectangular shape, as illustrated most clearly in Fig. 13, which is provided with a central opening 38 for mounting it on the end of the expansion member 26 within the interior of the housing-member 36. The element 65 has lateral flanges 66 folded up from its longer sides and adapted to engage through the rectangular opening 38 in the member 36 when the member 26 is turned to the position shown in Figs. 11 and 12. A spiral spring 68 is arranged between the rearward side of the element 65 and the outer face of the end-disk 53 with its larger end surrounding the bearing opening 27 in said disk. One end of the element 65 is formed with prongs 69 and 70 adapted to strike against the inner rim of the flange 11 on the disk 53 to limit the turning movement of the expansion member 26 in opposite directions, see Figs. 12 and 13.

When the expansion member 26 is turned to the position illustrated in Figs. 11 and 12 with the mandrel expanded the key 35 can be placed on the end of the expansion member and pushed through the opening 38 in the housing 36 a sufficient distance to allow it to be turned to contract the sleeve 20. The entrance of the shank 39 of the key 35 through the opening 38 acts to force the element 65 rearwardly on the member 26 and when the key has been inserted a sufficient distance it can be turned in counter-clockwise direction with the edges of the opening 38 engaging the slots 41 in the shank of the key. Such turning of the key 35 will rotate the member 26 through an arc of ninety degrees into the position shown in Fig. 13. As the member 26 is turned to this position, illustrated in Fig. 13, its arcuate edges are released from the terminal portions 21 of the sleeve 20 to permit the latter to contract under the influence of its inherent resiliency and the key 35 is locked to the mandrel by the engagement of the edges of the opening 38 in the housing member 36 with the slots 41 in the shank of the key. The cop-tube T can then be slid onto the periphery of the mandrel 75

into the position shown in Fig. 11 and then by turning the key 35 in clockwise direction the expansion member 26 will be rotated through an arc of ninety degrees to the position shown in Fig. 12 with the prong 69 bringing up against the inner rim of the flange 11 on the disk 53 to prevent further turning movement of the expansion member. Likewise, the key 35 may be turned in counter-clockwise direction to expand the sleeve 20 with this form of construction, its turning motion being limited by the engagement of the prong 70 with the inner rim of the flange 11. The turning of the member 26 in either direction causes its rounded edges to pry against the terminal portions 21 of the sleeve 20 to expand the latter to securely grip the cop-tube T for rotation with the mandrel. The turning of the key 35 will also align its rectangular shank 39 with the opening 38 in the housing 36 to permit the key to be detached from the mandrel and as its shank is withdrawn from the opening 38 the spring 68 will slide the locking element 65 outwardly on the end of the member 26 to engage its flanges 66 through the opening 38. The flanges 66 when thus engaged with the edges of the opening 38 will prevent unwarranted turning movement of the member 26 while the sleeve 20 is expanded to grip the cop-tube T. It has been found that this latter preferred form of construction of the means for controlling the turning motion of the expansion member 26 and locking it in position with the shell 20 of the mandrel expanded provides a more positive action of the expansion means and insures against release of the tube by accidental or unwarranted contraction of the sleeve 20.

The first described form of construction of the invention operates in substantially the same manner as above explained. Assuming that the outer sleeve or shell 20 of the mandrel is in its contracted relationship, as indicated in Figs. 7, 8 and 9, the paper or fiber cop-tube T is slid over its exterior in the manner indicated in Fig. 6 until its end abuts the radial flange 14 on the head 3. In contracting the shell 20 of the mandrel the shank 39 of the key 35 has been inserted through the slot 38 in the housing-member 36 and turned to the position illustrated in Figs. 6 to 9 so that the key is locked to the mandrel by the engagement of the edges of the opening 38 with the notches 41 in its shank, see Fig. 7. After the tube T has been slid into place on the mandrel the key 35 is turned in clockwise direction, as viewed in Fig. 7, to rotate the expansion member 26 through an arc of ninety degrees, thereby causing the rounded edges of said member to ride against the terminal portions 21 of the sleeve 20 to cam them apart and thus expand the sleeve in the manner indicated in Figs. 4 and 5. This turning movement of the expansion member 26 is limited by the rotation of the disk 42, shown in Figs. 2, 3 and 7, to cause its slightly flattened face 43 to move from the position shown in Fig. 7 to that illustrated in Fig. 3.

With either form of construction the expansion of the sleeve or shell 20 will cause it to bind firmly against the interior wall of the cop-tube T while adjusting itself concentrically with the axis of the mandrel. The cop-tube T is thus firmly gripped and held concentric with the axis of the mandrel to receive the yarn or other strand material to be wound thereon. The key 35, when locked in connection with the mandrel, may be used as a handle to place the cop-tube on the mandrel or to remove the tube and wound package therefrom.

In case the operator has neglected to expand the mandrel to a sufficient extent to grip the tube T the key will remain locked to the end of the mandrel so that the latter cannot rotate when placed in its bearings. It will be observed therefore, that the key serves as a precautionary measure against neglect to expand the mandrel in preparing it for operation.

Usually, in winding packages of textile materials the first end of the yarn is wound around the flange 16 at the end of the mandrel in the V-shaped groove 17. This provides a reserve length or "tail" of yarn which may be used for splicing one package to another when the yarn is delivered as a supply and the packages magazine on a creel or other support. The length of yarn wound in the groove 17 in the flange 16 serves to bind it to the holder so that when the latter is rotated with the cop-tube T the yarn will be wound therearound to build it up in a cop or package such as indicated at P in Fig. 1.

It will be observed from the foregoing specification that the present invention provides a novel and ingenious construction of expansible mandrel or cop-holder which is most convenient to operate and highly efficient in use for the purposes intended. In addition, the present improved structure provides a holder of rugged construction, and proof against derangement or getting out of order.

While the invention is described and illustrated herein as embodied in one preferred form of construction with a modified form also shown, it is to be understood that various further modifications may be made in the structure and arrangement of the parts of the device without departing from the spirit or scope of the invention. Therefore, without limiting ourselves in this respect, we claim:

1. A mandrel or cop-holder comprising a supporting structure, means expansible on the periphery of said structure to grip the cop-tube, a rotatable expansion member for operating said means, a key engageable with said expansion member to rotate the latter, means for automatically locking said expansion member against rotation when the key is withdrawn, and means for locking the key in connection with the expansion member when the expansible means is contracted.

2. An expansible mandrel or cop-holder comprising a supporting structure, a cylindrical sleeve supported from said structure and split longitudinally to provide for its expansion and contraction circumferentially, an expansion member rotatable between the sides of the split portion of the sleeve to expand the latter, a removable key for turning the expansion member to expand or contract the sleeve, and means actuated by the removal of the key to positively lock the expansion member in position to maintain the sleeve expanded until the key is again applied thereto.

3. In an expansible mandrel or cop-holder, the combination of a supporting structure, a cylindrical sleeve supported from said structure and split longitudinally to adapt it to be expanded circumferentially, an expansion member engaging the split portion of the sleeve and rotatable to expand and contract the latter, a removable key engageable with said expansion member to turn the latter, and means on the mandrel cooperating automatically with the key to lock the latter to the mandrel when it is turned to contract the expansible sleeve.

4. An expansible mandrel or cop-holder comprising a supporting structure, a cylindrical sleeve

supported from said structure and split longitudinally to adapt it to be expanded and contracted circumferentially, an expansion member engaging the split portion of the sleeve and rotatable to expand or contract the latter, and resilient means independent of the sleeve and acting directly on the expansion member to prevent turning of the latter beyond the extent required to fully expand the sleeve.

5. An expansible mandrel or cop-holder comprising a supporting structure, a substantially cylindrical sleeve supported from said structure and split longitudinally to adapt it to be expanded circumferentially, an expansion member engageable with the sides of the split portion of the sleeve and rotatable to expand the latter, means engageable with said expansion member to turn the latter, said expansion member having a flat portion, and resilient means engageable with the flat portion of the expansion member to limit the extent of turning movement of the expansion member beyond that required to expand the sleeve.

6. An expansible mandrel or cop-holder comprising a supporting structure having spaced-apart end-heads, a cylindrical sleeve supported from said end-heads and split longitudinally to adapt it to be expanded or contracted circumferentially, a rotatable expansion member extending between the sides of the split portion of the sleeve and engageable therewith to expand the sleeve, said expansion member projecting beyond one of the end-heads, a housing enclosing the end of the expansion member projecting beyond the end-head, said housing having an elongate opening surrounding the expansion member, and a key shaped to engage over the end of the expansion member and having notches adapted to be engaged by the edges of the housing surrounding the opening therein to lock the key to the mandrel when it is turned to effect contraction of the expansible sleeve.

7. An expansible mandrel or cop-holder comprising spaced-apart end-heads, a cylindrical sleeve of sheet-metal surrounding the periphery of the end-heads and split longitudinally to adapt it to be expanded and contracted circumferentially, the sides of the split portion of the sleeve being folded inwardly in opposed relationship to provide spaced substantially radial flanges, an expansion member rotatable in bearings in the end-heads and extending between the flanges of the sleeve to adapt it to expand the latter, said member being formed with opposite flat sides to adapt it to be turned to permit contraction of the sleeve, and a spring secured to one of the end-heads and having a portion extending across the end of the expansion member and adapted to engage the flat side thereof to prevent self-rotative movement of the member after it is turned to expand the sleeve and the key is withdrawn.

8. An expansible mandrel or cop-holder comprising a supporting structure, a cylindrical sleeve supported from said structure and split longitudinally to adapt it to be expanded circumferentially, a longitudinally extending expansion member mounted in the supporting structure and rotatable between the sides of the split portion of the sleeve to expand and contract the latter, said expansion member having one end projecting beyond the supporting structure, a housing member at one end of the mandrel having an opening surrounding the projecting end of the expansion member, and a key adapted to engage the end of the expansion member by inserting it through

the opening in the housing member, said key being provided with slots in its sides for engaging with the housing at the sides of the opening therein to lock the key in connection with the mandrel when it is turned to contract the sleeve.

9. A mandrel or cop-holder comprising a supporting structure, an expansible sleeve supported from said structure, a longitudinally extending expansion member mounted to rotate in the supporting structure to expand the sleeve and having one end projecting therebeyond, a housing member at one end of the mandrel provided with an opening enclosing the projecting end of the expansion member, a locking element slidable on the projecting end of the expansion member and provided with means adapted to engage through the opening in the housing member when the expansion member is turned to position to expand the sleeve, and a spring for sliding the locking element on the expansion member to engage it with the opening in the housing member, a key adapted to be inserted through the opening in the housing and engageable with the expansion member, said locking element being adapted to be slid inwardly on the expansion member to release it from the opening in the housing member by the insertion of the key through said opening.

10. An expansible mandrel or cop-holder com-

prising a supporting structure having spaced end-heads, a cylindrical sleeve extending between said heads and supported thereby, said sleeve being split longitudinally to adapt it to expand and contract circumferentially, an expansion member extending longitudinally between the sides of the split portion of the sleeve and rotatably mounted in bearings in the end-heads, said expansion member having one end projecting through one of the end-heads, a housing member secured to said last-mentioned end-head and formed with a rectangular opening enclosing the end of the expansion member projecting through said end-head, a locking element slidable on the end of the expansion member and formed with projections adapted to engage the housing at the sides of the opening therein to lock the expansion member from turning movement when the latter is turned to expand the sleeve, a spring for sliding the locking element to engage its projections with said opening, and a key fitted to engage the end of the expansion member and to enter through the opening in the housing member to release the locking element from engagement therewith whereby to permit turning movement of the expansion member to contract the sleeve.
